UNITED STATES PATENT OFFICE.

WILLIAM J. WHITESIDE, OF KEEWATIN, MINNESOTA.

GLASS-GAGE PROTECTOR.

1,382,582.

Specification of Letters Patent. Patented June 21, 1921.

Application filed July 12, 1919. Serial No. 310,367.

To all whom it may concern:

Be it known that I, WILLIAM J. WHITESIDE, a citizen of the United States, residing at Keewatin, in the county of Itasca and 5 State of Minnesota, have invented certain new and useful Improvements in Glass-Gage Protectors, of which the following is a specification.

This invention relates to improvements in 10 water gages for steam boilers and more particularly to a device for protecting the glass tube of such a gage so as to prevent fracture of the tube through contact with other objects and likewise prevent, to a considerable 15 extent, scattering of the glass in the event of bursting of the tube.

One of the objects of the present invention is to provide a gage protector for the purpose stated comprising head members for 20 assemblage with the ends of the glass tube of the gage, and means connecting the said members for protecting the said tube, the said connecting means being adjustable as to 25 length so as to permit of the application of the device to gage tubes of various lengths.

In the accompanying drawings:

Figure 1 is a view partly in side elevation and partly in vertical section illustrating the device embodying the present invention;

30 Fig. 2 is a horizontal sectional view taken substantially on the line 2—2 of Fig. 1;

Fig. 3 is a detail horizontal sectional view through one of the adjustable protector bars, the view being taken substantially on the 35 line 3—3 of Fig. 1.

In the drawings the gage tube is indicated by the numeral 1 and is as usual of glass so that the height of the water level therein may be readily observed. The numerals 2 and 3 indicate pipes which are respectively 40 placed in communication with the boiler above and below the normal water line therein, and these pipes have enlarged ends 4 which fit the respective ends of the gage tube 1, as shown in Fig. 1 of the drawings. The device embodying the present invention includes two head members, one indicated by the numeral 5 and the other by the numeral 6, these members being each provided with a 45 bore and being respectively disposed to fit the upper and lower ends of the gage tube. Each of the members is interiorly increased in diameter at its outer end as indicated by the numeral 7 to receive a packing 8 engaged by the enlarged end of the respective pipes 2 and 3 as the case may be. The

said head members 5 and 6 are also exteriorly threaded as indicated by the numeral 9, and cap nuts 10 are fitted thereto and may be tightened to draw the said pipes and the 60 respective heads together thus forming a water-tight seal at the ends of the gage tube. The head members 5 and 6 are respectively provided at their lower and upper portions with polygonal extensions 11 to the 65 faces of which are secured the ends of the faces of which are secured the ends of the 70 protector bars as will now be described.

Each of the bars referred to above, indicated in general by the numeral 12, comprises a pair of relatively adjustable sections, one of said sections being indicated by the numeral 13 and the other by the numeral 14. Each section 14 is in the nature of a length of bar material having beveled lateral edges 15, these sections being secured 75 at their upper ends as at 16 to the extension 11 of the upper head 5, as clearly shown in Fig. 1 of the drawings. Each of the sections 13 is in the nature of a relatively flat bar provided at its lateral edges with inwardly directed flanges 17 the inner faces of which are inclined so as to provide at the rear side of each of the said sections 13 a longitudinally extending channel having inclined walls to fit the beveled edges 15 of 80 the sections 14. In this manner the paired sections 13 and 14 are slidably connected so that the protecting bar may be adjusted as to length. The sections 13 are secured at 85 their lower ends as at 18 to the faces of the extension 11 of the head member 6, and in order that the sections comprising each bar may be held at adjustment, threaded studs 19 are provided upon the sections 14 and fit through longitudinally extending slots 20 90 formed in the sections 13, wing or similar nuts 21 being threaded onto the said studs and being adapted to be tightened to bear against washers 22 which in turn bear against the outer faces of the respective sections 13. It will be observed by reference to 95 Figs. 1 and 2 of the drawings that adjacent edges of the protecting bars are sufficiently spaced to permit of the water level in the gage tube being observed and yet these bars 100 constitute an effective guard to prevent any object striking the tube and causing fracture thereof, and at the same time the spaces between the bars are sufficiently narrow to provide against any considerable scattering 105 of the glass in the event of bursting of the 110 gage tube.

Having thus described the invention, what is claimed as new is:

In a device of the class described, head members provided at their adjacent ends with polygonal extensions, projecting members extending between the head members and each comprising a section secured at one end to one face of the polygonal extension of one of the head members, and 5 a section secured at one end to the corresponding polygonal face of the other head member, the sections overlapping and one 10

of the sections being provided with marginal flanges to engage the lateral edges of the other section, one of the said sections being 15 slotted longitudinally, a threaded stud carried by the other section and projecting through the slot, and a nut threaded upon the stud to bear against the slotted section.

In testimony whereof I affix my signature. 20

WILLIAM J. WHITESIDE.

Witnesses.
